CASING FOR A MARKER PEN

Moto Shimano and Clarence D. Zierhut, Los Angeles,
Calif., assignors to The Gillette Company, Santa
Monica, Calif., a corporation of Delaware

Filed July 14, 1969, Ser. No. 18,199

Term of patent 14 years

Int. Cl. D19—06

U.S. Cl. D74—17

FIG. 1 is an elevational view of a casing for a marker pen showing our new design:

FIG. 2 is a top plan view thereof looking in the direction of the arrow 2 on FIG. 1; and

FIG. 3 is a bottom plan view looking in the direction of the arrow 3 on FIG. 1.

We claim:

The ornamental design for a casing for a marker pen, as shown.
